UNITED STATES PATENT OFFICE.

ROLLIN H. WHITE, OF CLEVELAND, OHIO, ASSIGNOR, BY MESNE ASSIGNMENTS, TO THE WHITE COMPANY, OF CLEVELAND, OHIO, A CORPORATION OF OHIO.

DRIVING MECHANISM FOR RAILWAY-CARS.

No. 921,491.

Specification of Letters Patent.

Patented May 11, 1909.

Application filed September 14, 1906. Serial No. 334,633.

To all whom it may concern:

Be it known that I, ROLLIN H. WHITE, a citizen of the United States, residing at Cleveland, in the county of Cuyahoga and 5 State of Ohio, have invented a certain new and useful Improvement in Driving Mechanism for Railway-Cars, of which the following is a full, clear, and exact description.

This invention is designed especially for 10 use in connection with self-propelled railway cars.

It relates to the mechanism, associated with one of the swiveled trucks of such a car, for transmitting motion from a motor on the 15 car to the wheels of such truck.

In the drawing Figure 1 is a plan view of the mechanism embodying this invention,—the top member of the casing being removed and a portion of the casing broken away. 20 Fig. 2 is a sectional side elevation in the plane indicated by line 2—2 on Fig. 1, and a central longitudinal section of the associated truck,—a portion of the casing D being broken away. Fig. 3 is a transverse sectional view in the plane indicated by line 3—3 on Fig. 1, and Fig. 4 is an end view, showing the driving shaft in vertical section, a portion of the lower casing member d^2 being broken away so as to show one of the caps 25 30 F' which forms a part of the bearing of the axle A. In Figs. 2 and 4 parts of the swiveling truck are shown in dotted lines. Fig. 5 is a sectional side view of one of the bearings of the axle B carried by the frame member d , 35 said section being in the plane indicated by line 5—5 on Fig. 1.

Referring to the parts by letters A and B represent the two axles, which are associated with, and support, in the usual way, one of 40 the swivel trucks C of a railway car; and a and b represent the wheels, which are respectively made fast to said two axles.

D represents a frame, in the form of a casing, in which said axles are rotatably 45 mounted, and which serves to maintain them in parallel relationship and at an invariable distance apart; and this casing also incloses and supports the mechanism by which said two axles are rotated.

50 The casing D is made up of three members $d—d'—d^2$. The member d is provided, near its ends, with the upper halves of the bearings F—F for the two axles. The lower halves F' of said bearings are secured by 55 bolts d^3 to the member d . The casing mem-

ber d and d' are secured together by bolts passing through marginal flanges thereon. Within this casing are two parallel longitudinally extended shafts E and G.

The shaft E is mounted near its ends in 60 bearings J and K respectively; the upper halves of which are formed in the casing member d . The lower halves of said bearings are formed by caps j and k which are secured by bolts or otherwise to the under 65 side of the casing member d . This shaft carries, at its ends, the beveled gears $e—e'$ for engagement with the beveled gears $a^2 b^2$, which are secured respectively to the two 70 axles, and are located, the one on one side 75 and the other on the other side of the axis of shaft E, whereby the rotation of said shaft will drive both axles in the same direction. The other shaft G is also mounted in bearings M and N, which are wholly supported by, the casing member d . In the construction shown the lower halves of said 80 bearings are formed in the top of the casing member d , while the upper halves of said bearings are caps secured to said member d . 85 This shaft projects out through the end of said casing; and the protruding end thereof is connected with a driving shaft H by means of a universal joint P. Both of the axes of 90 this universal joint are in the same transverse vertical plane with the axis O of the king bolt upon which the truck C swivels. The turning of the truck, therefore, upon its axis, does not interrupt or affect the transmission of motion to shaft G from the driving shaft H, even though said driving shaft receives its motion from a motor upon a car 95 supported upon said truck.

It has not been thought necessary to show the car or the motor, because they are no 95 part of the present invention; nor has it been thought necessary to show the universal joint which it would probably be necessary to use for connecting shaft H with some longitudinal shaft on the car driven by the 100 motor.

The shaft G is provided with collars g^3 , which prevent endwise movement of said shaft within its bearings. Two gears $g—g'$ of different diameter are secured to shaft G 105 within the casing. An adjacent portion e^5 of shaft E is made square; and upon this squared portion is a sliding sleeve R carrying two gears $r—r'$ of different diameters, and adapted to engage respectively with the 110

gears g g' . This sleeve R is provided with an annular groove r^2 into which project pins t carried by a forked arm t' ,—said arm being secured, within the casing, to the lower end 5 of an operating shaft T, which is mounted in a suitable bearing d^3 in the casing member d. By operating shaft T, the sleeve R is moved longitudinally in either direction so that its gears may severally engage with the 10 gears g or g' as required to change the ratio between the speeds of shaft G and shaft E.

It will be seen from the foregoing description that the mechanism within the casing D is supported wholly by the casing member d; 15 and, therefore, said mechanism may all be mounted and adjusted in said casing member before the same is connected up with the axles. The casing members d' d^2 may be removed in order to get at the inclosed 20 mechanism for adjustment or repair without changing the operative relationship of the inclosed mechanism.

Having described my invention, I claim:

1. The combination with a swiveling car 25 truck, the two axles upon which it is supported, and wheels secured to said axles, of a frame which rests upon and is supported by said axles and has bearings in which the axles rotate, a longitudinally extended shaft 30 which is mounted in bearings upon said frame, mechanism supported by said frame for transmitting motion from said shaft to one or both of the axles, a driving shaft, and a universal joint connecting said shafts and 35 having its pivots in substantially the same transverse vertical plane as that which contains the axis of the truck king bolt.

2. The combination with a swiveling car 40 truck, the two axles upon which it is supported, and wheels secured to said axles, of a frame which rests upon said axles and has bearings in which they rotate, a longitudinally extended shaft mounted in bearings upon said frame and having beveled gears 45 secured to its end, mechanism for rotating said shaft, and beveled gears secured respectively to said axles on opposite sides of the axis of said shaft and in mesh with the beveled gears thereon, and mechanism by which motion 50 may be transmitted to said shaft from a motor on the car to which said truck is swiveled.

3. The combination with a swiveling car 55 truck, the two axles upon which it is supported, and wheels secured to said axles, of a casing which rests upon said axles and has bearings in which they rotate,—said casing being composed of separable parts, a longitudinally extended shaft which projects 60 through the casing wall and is mounted in bearings within the casing, mechanism for rotating said shaft, and mechanism within the casing for transmitting motion from said shaft to both axles.

4. The combination with a swiveling car 65 truck, the two axles upon which it is supported, and wheels secured to said axles, of a frame which rests upon said axles and has bearings in which they rotate, a longitudinally extended shaft which is mounted in 70 bearings upon said frame, mechanism for rotating said shaft, gears secured to said shaft, another longitudinal shaft mounted in bearings upon said frame, a sleeve which is slideable upon said shaft and is connected therewith by means which compel it to rotate with the shaft, gears fast to said sleeve, and mechanism mounted upon the frame for moving said sleeve along said shaft.

5. The combination with a swiveling car 80 truck, the two axles upon which it is supported, and wheels secured to said axles, of a casing consisting of a middle member which rests upon said axles and carries bearings in which they rotate, a removable bottom section, and a removable top section, two parallel shafts within the casing mounted in bearings supported wholly by the middle section,—one of said shafts being extended out of the casing,—mechanism within the 90 casing for transmitting motion from that shaft to the other shaft, mechanism for transmitting motion from the last named shaft to both axles, a driving shaft outside of said casing, and a universal joint connecting said driving shaft with the projecting end of the shaft first mentioned, said universal joint being located substantially as described where a prolongation of the axis of the truck king bolt will intersect said universal joint centrally.

6. The combination with a swiveling car 105 truck, the two axles upon which it is supported, and wheels secured to said axles, of a casing which is secured upon said axles and has bearings in which they rotate, the longitudinal shaft G mounted in bearings within said casing and having one end protruding therefrom, two gears fixed to said shaft within the casing, the longitudinal shaft E 110 mounted in bearings within the casing, two beveled gears secured to its ends respectively, a sleeve slideable upon the last mentioned shaft but compelled to rotate with it, two gears fast to said sleeve, an operating 115 spindle rotatably mounted in the casing and projecting from the outside into the casing, a forked lever secured to the inner end of said spindle for operating said sliding sleeve, and beveled gears secured to the axles and 120 meshing with the beveled gears upon said shaft.

In testimony whereof, I hereunto affix my signature in the presence of two witnesses.

ROLLIN H. WHITE.
